DESIGN FOR A SPRING HAIR CURL CLIP

Hazel M. Lundquist, San Francisco, Calif.

Application April 10, 1943, Serial No. 109,950

Term of patent 7 years

To all whom it may concern:

Be it known that I, Hazel M. Lundquist, a citizen of the United States and a resident of the city and county of San Francisco, State of California, have invented a new, original, and ornamental Design for a Spring Hair Curl Clip, of which the following is a specification, reference being had to the accompanying drawing, forming a part thereof.

Fig. 1 is a perspective view of a spring hair curl clip in heroic size showing my new design.

Fig. 2 is a plan view of the clip.

Fig. 3 is a side view of the clip.

I claim:

The ornamental design for a spring hair curl clip, substantially as shown.

HAZEL M. LUNDQUIST.
